US0D1112167S

(12) **United States Design Patent** (10) **Patent No.:** **US D1,112,167 S**
(45) **Date of Patent:** **** Feb. 10, 2026**

(54) **WIRELESS EARPHONE**

(71) Applicant: **Samsung Electronics Co., Ltd.**, Suwon-si (KR)

(72) Inventors: **Sanhui Oh**, Suwon-si (KR); **Sangok Sohn**, Suwon-si (KR); **Kyubok Lee**, Suwon-si (KR); **Juan Lee**, Suwon-si (KR); **Jinwook Kim**, Suwon-si (KR); **Dongjae Koo**, Suwon-si (KR)

(73) Assignee: **Samsung Electronics Co., Ltd.**, Suwon-si (KR)

(**) Term: **15 Years**

(21) Appl. No.: **29/956,602**

(22) Filed: **Aug. 8, 2024**

(30) **Foreign Application Priority Data**

Jun. 11, 2024 (KR) 30-2024-0022749

(51) **LOC (15) Cl.** **14-01**

(52) **U.S. Cl.**

USPC **D14/223**

(58) **Field of Classification Search**

USPC D14/202, 205, 206, 223

CPC H04R 1/10; H04R 1/1016; H04R 1/2842

See application file for complete search history.

(57) **CLAIM**

The ornamental design for a wireless earphone, as shown and described.

DESCRIPTION

FIG. 1 is a front perspective view of a wireless earphone showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The broken lines in the figures depict portions of a wireless earphone that form no part of the claimed design.

1 Claim, 4 Drawing Sheets
